UNITED STATES PATENT OFFICE.

JOHN MAGNAULL WILSON, OF NEWARK, NEW JERSEY.

METHOD OF CAR-CLEANING.

1,372,988.

Specification of Letters Patent. Patented Mar. 29, 1921.

Application filed March 7, 1919. Serial No. 281,304.

To all whom it may concern:

Be it known that I, JOHN MAGNAULL WILSON, a citizen of the United States, residing at Newark, in the county of Essex, 5 State of New Jersey, have invented certain new and useful Improvements in Methods of Car-Cleaning; and I do hereby declare the following to be a full, clear, and exact description of the invention, such as will 10 enable others skilled in the art to which it appertains to make and use the same.

My invention relates to a cleaning method, and has among other objects the purpose of increasing efficiency in cleaning the 15 surface of cars and the like, preserving and restoring the finish thereof and leaving it in a brilliant condition comparable with its original appearance.

Further objects and advantages of my 20 invention will be apparent, as it is better understood, by reference to the following specification in which the best modes of procedure according to my invention are described, a cleaning device capable of use 25 in connection therewith being illustrated in the drawing, in which—

Figure 1 is a view in perspective of a rotary power driven brush and

Fig. 2 is a transverse section there- 30 through.

The surface of railway passenger cars become more or less discolored and stained in service and must be cleaned periodically to present a reasonably pleasing appear- 35 ance, as well as an economic measure to preserve the varnished surface and reduce ex- pense of repainting. Various expedients have been resorted to in the treatment of such surfaces. Alkalies and soapy mixtures 40 suggest themselves but are particularly damaging to varnished surfaces and are therefore to be avoided. Water alone is inefficient since it removes only superficial dust or dirt leaving oil, grease or other 45 stains to accumulate. Neutral oil and grease cleaners with or without abrasives are only effective when the surface is ener- getically scrubbed therewith, which in- creases labor expenses. Neutral oil and

50 grease cleaners, moreover, leave a moist non-drying finish, only serving to attract and hold more dust and dirt, which with gas absorbed eventually stains the surface. Solu- 55 tions of oxalic acid in water have been tried but are detrimental to the varnished surface unless the latter is thoroughly

rinsed. The problem of cleaning windows is also present and none of the foregoing means is suitable for this purpose, having in mind the adjacent varnished surfaces 60 which are more or less injured by careless use of the cleaning materials.

I have discovered that suitable acid solu- 65 tions may be safely and efficiently used in conjunction with a novel cleaning compo- 70 sition or emulsion which I have devised. This composition or emulsion is of a character which neutralizes any free acid re- maining after the preliminary treatment therewith and, in addition, differing from 75 oil, provides a drying body comparable with varnish, which preserves the varnished surface and leaves it in a condition approxi- mating its original brilliancy.

My composition is, moreover, of a nature 75 which permits of its use alone as a deter- gent, so that it may be employed without acid to clean varnished and similar surfaces. It may be used successfully upon windows without preliminary treatment with oxalic 80 acid and when the latter is employed the subsequent treatment with my composition or emulsion neutralizes the acid and insures the preservation and restoration of the sur- 85 rounding varnished surfaces. A compo- 90 sition or emulsion which I have found to be well adapted to accomplish the desired re- sults may comprise certain ingredients, hereinafter specified, for which various equivalents may be substituted. Other 95 changes, such as the omission of one or more of the ingredients or variation of the proportions thereof, may be made without departing from the invention, it being essen- 100 tial only that the composition or emulsion has the properties of acting as a cleansing agent and providing a drying body capable of producing a dry glossy finished surface. When used in connection with a preliminary treatment with suitable acid, the compo- 105 sition or emulsion should also be capable of neutralizing any such acid remaining on the surface.

My composition or emulsion being capable of use either with or without preliminary 105 treatment with oxalic or other acid having detergent properties, may obviously be used in connection with cleaning agents, other than oxalic acid, and such use is contem- 110 plated by me. It is my intention, therefore to include in this application the compo- 115 sition or emulsion with such variations in its

composition as may be expedient, having in mind its intended purpose and the variation in the character of surfaces to which it may be applied. It is my further intention to include the use of such composition or emulsion, either alone or in connection with a preliminary treatment, with oxalic acid or other cleaning material.

In order that my invention may be fully understood and practised, without recourse to experiment, I shall describe a composition or emulsion which has proven entirely successful in the practical application of my invention, together with an example of its application. It is to be understood that such description is by way of example only and is not to be considered as the sole available composition or method of applying the same.

20 My composition or emulsion may comprise, for example, the following ingredients in the proportions mentioned:

Pine oil	15.5%
Paraffin or mineral oil	53.0%
Lime soap made from whale oil	13.5%
Turpentine	5.5%
Water	13.0%

A proportion of mineral abrasive or pulverized soap bark may, if desired, be included in the composition.

Such a composition, the ingredients of which are thoroughly incorporated or emulsified, is itself a detergent and may be used for cleansing surfaces of various kinds. It embodies sufficient oil of a drying character to form a brilliant film on a varnished surface. This film is substantially water and weather proof, does not collect and hold dust, and when the original varnish is not wholly destroyed, treatment with the composition or emulsion will restore the varnish to substantially its original condition.

In the preferred mode of employing my composition or emulsion, the surface to be cleaned is first treated with a solution of oxalic or equivalent detergent acid or cleansing agent. This treatment loosens the dirt and stains without scrubbing or other laborious treatment. After the acid has remained on the surface for a short period and preferably before drying, the surface is coated with the composition or emulsion. This surface is then wiped clean with waste or other suitable material, leaving the surface clean and dry and with a permanent high gloss which has the appearance of a fresh coat of varnish.

The composition or emulsion destroys the acid remaining on the surface, so that it can have no deleterious effect upon the varnish or metal construction of the car. It is not, therefore, essential to rinse the surface with water following the treatment with acid. Nevertheless, rinsing may be practised, if

considered desirable, and will not adversely affect the results accomplished with the emulsion following.

Under certain conditions, as where the surface is badly discolored, it is expedient and desirable to mechanically brush the surface treated. I have, therefore, provided a device particularly adapted to the accomplishment of this object, with a minimum application of labor. This device is illustrated in the accompanying drawing, in which 5 indicates a casing supporting a spindle 6 for a turbine or similar wheel 7 adapted to be driven by an air blast entering from any suitable source of supply through an inlet 8 provided with a valve 9 and exhausting through an outlet 10. A pinion 11 connected to the turbine wheel 7 meshes with a gear 12 on a shaft 13 carrying a brush 14 which is adapted to be rotated through a connection with the turbine wheel 7, at a speed of approximately 1000 R. P. M. Handles 15 are provided at opposite sides of the casing 5, whereby the bristle brush 14 may be firmly held in engagement with the work or swept over it as desired, the object being to clean the surface, rivet and bolt heads with great rapidity and thoroughness. An electrically driven portable motor will answer the same purpose as an air motor and may be substituted therefor.

In an embodiment of my method, the surface, after preliminary treatment with oxalic acid or other acid or cleanser, is brushed, preferably with the mechanical device illustrated and described herein, though possibly by a hand scrubbing brush, until all dirt and stains have been removed. The surface is then, either following or without rinsing, coated with the composition or emulsion herein described or its equivalent and immediately wiped off with the waste or other suitable material leaving a dry highly polished surface.

My invention is particularly useful in carrying out the cleaning of car surfaces during the winter months. Such work is generally carried out in unheated buildings or possibly in yards, and during periods of low temperatures the possibility of freezing precludes the use of water in cleaning operations. Under such conditions I preferably mix with the acid solution a relatively slight percentage of commercial glycerin, for example, 2 to 4 ounces per gallon of solution. I have discovered that the addition of glycerin to the solution precludes freezing in the coldest weather and also retards drying of the solution thus permitting it to more effectively accomplish its purpose. The prevention of freezing is highly important in cold weather as it materially reduces the labor required in cleaning cars. The addition of glycerin is equally advan-

tageous in summer to retard drying of the acid solution. When the acid solution containing glycerin is employed, it may be followed by a treatment with the composition 5 or emulsion hereinbefore described. If there is danger of freezing intermediate rinsing with water is omitted. In warmer weather an intermediate rinse with water may be employed or not as desired. As will be noted, 10 my method requires no water for the successful cleaning and restoring of car surfaces. Thus, the most difficult problems in car cleaning are fully met by my invention in eliminating water and establishing a high 15 and dry gloss on the finished surface likewise in neutralizing the possible corrosive action of acid.

Various modifications of the emulsion composition and mechanical method described herein will suggest themselves in the application of my invention under peculiar conditions, which may arise from time to time in cleaning surfaces of varying character. Such modifications, within the scope 25 of the appended claims, may be made without departing from the spirit or scope of the invention or sacrificing any of its material advantages.

I claim:—

30 1. A method of cleaning surfaces which comprises treating the surface with a cleansing agent and subsequently applying a composition thereto capable of neutralizing said agent and forming a dry lustrous film on 35 said surface when the surplus of said composition is removed.

2. A method of cleansing surfaces which comprises treating the surface with a water solution of an acid cleansing agent and subsequently applying an emulsion thereto capable of forming a lustrous film on said surface when the surplus of said emulsion is removed.

3. A method of cleansing surfaces which 45 comprises treating the surface with a water solution of an acid and subsequently applying an emulsion embodying a neutralizing agent for said acid and a drying body capable of forming a lustrous film on said 50 surface when the surplus of said emulsion is removed.

4. A method of cleaning surfaces which comprises treating the surface with an acid cleansing agent, rinsing said surface and

subsequently applying a composition capable of neutralizing any remaining acid and of forming a lustrous film on said surface when the surplus of said composition is removed.

5. A method of cleaning surfaces which 60 comprises treating the surface with a cleansing agent, scrubbing the surface and subsequently applying an emulsion capable of forming a lustrous film on said surface when the surplus of said emulsion is removed. 65

6. A method of cleansing surfaces which comprises treating the surface with an acid solution containing a non-drying ingredient and subsequently applying a composition capable of neutralizing said acid and forming 70 a dry lustrous film on said surface when the surplus of said composition is removed.

7. A method of cleansing surfaces which comprises treating the surface with an acid solution containing a proportion of glycerin 75 and subsequently applying a composition capable of neutralizing said acid and forming a dry lustrous film on said surface when the surplus of said composition is removed.

8. A method of cleansing surfaces which 80 comprises treating the surface with a cleansing agent containing a small proportion of glycerin and subsequently applying a composition capable of forming a dry lustrous film on said surface when the surplus of said 85 composition is removed.

9. A method of cleansing surfaces which comprises treating the surface with a cleansing agent containing a proportion of glycerin, subsequently applying a composition 90 capable of forming a dry lustrous film on said surface when the surplus of said composition is removed, brushing said surface while said composition remains in contact therewith and removing the surplus of said 95 composition.

10. A method of cleaning surfaces which comprises, treating the surface with a cleansing agent, subjecting the surface to the scrubbing action of a mechanically driven 100 brush while coated with said cleansing agent and subsequently applying a composition capable of neutralizing any remaining acid and of forming a lustrous film on said surface when the surplus of said composition is 105 removed.

In testimony whereof I affix my signature.
JOHN MACNAULL WILSON.
